MASSAGE DEVICE

Henry G. Hilsher and Ruth S. Hilsher,
Baltimore, Md.

Application December 16, 1949, Serial No. 133,306

5 Claims. (Cl. 128—57)

1

This invention relates to an improved manual massage device of the roller type, the primary object of the invention being to provide a more efficient and practical device of this kind which affords substantially greater and more beneficial massage and manipulation of the body surfaces and the tissues and muscles underlying such surfaces and which more accurately follows the contours of the body.

Other important objects and advantageous features of the invention will be apparent from the following description and the accompanying drawings, wherein, for purposes of illustration only, a specific embodiment of the invention is set forth in detail.

In the drawings:

Figure 1 is a top plan view.

Figure 2 is an end elevation.

Figure 3 is a transverse vertical section taken on the line 3—3 of Figure 4.

Figure 4 is a vertical longitudinal section taken on the line 4—4 of Figure 1.

Referring in detail to the drawings, wherein like numerals designate like parts throughout the several views, the illustrated device comprises a frame composed of two similar, longitudinally elongated plate-like side members 5, 5 having central ears 6 on their upper edges, and having four equally longitudinally spaced projections 7 on their lower edges. The side members 5 are rigidly and parallelly spaced and connected together by rods 8 having threaded ends 9 traversing the side members between the projections 7, and spacing tabs 8' in the rods, with cap nuts 10 threaded on the rod ends against the outer sides of the side members.

A hand pad 11 in the form of a plane rectangular rigid plate having rounded corners 12 is positioned above and extends between the frame side members 5 and extends between the opposite ends thereof and has central depending lugs 13 on its opposite side edges which lie along the inward sides of the ears 6. Pivots 14 traverse the ears 6 and the lugs 13 whereby the hand pad 11 is spaced upwardly from the side members and is free to rock relative thereto on an axis extending transversely of the device. Stop lugs 15 project from and depend from the opposite side edges of the hand pad 11 near the ends thereof to engage the upper edges 16 of the side members 5 to limit rocking of the hand pad 11 in opposite directions.

The hand pad 11 has slotted ears 17 rising from the opposite sides thereof over the ears 6 through which are secured the opposite ends of an elastic

band 18 arranged to overlie and grip the back of the hand of the masseur with the palm of the hand engaged with the top of the hand pad 11, whereby the device is properly held in the hand for massaging portions of the body.

Four transverse rollers 19 are parallelly and equally spaced along and between the side members 5. Each roller 19 has an angulated axle 19' having a concentric or axial end 20 projecting from one end and an eccentric end 21 projecting from its opposite end. The projections 7 on the lower edges of the side members 5 have journal holes 22 located in the same horizontal plane, in which the pintle ends 20 and 21 are journaled. 10 Alternate ones of the rollers are reversed in position so that the concentric pintles 20 and eccentric pintles 21 of adjacent rollers are journaled in opposite ones of the side members whereby the adjacent rollers are pitched at opposite angles. As a result when the device is moved over a body surface the rollers 19 roll in contact therewith at different angles. At the same time the frame of the device is free to rock relative to the hand pad 11 so as to follow the contours of 25 the body surface.

What is claimed is:

1. A massage device comprising a frame having spaced side members, a hand pad extending between said side members and pivoted to said frame to rock on a transverse axis relative to said frame, and a plurality of transverse axis rollers extending transversely between said side members beneath said hand pad, said rollers having opposite ends thereof journaled on said side members, adjacent ones of said rollers having ends thereof concentrically journaled on opposite ones of said side members and having opposite ends thereof eccentrically journaled on opposite ones of said side members.

40 2. A massage device comprising a frame having spaced side members, a hand pad extending between said side members and pivoted to said frame to rock on a transverse axis relative to said frame, a plurality of transverse axis rollers extending transversely between said side members beneath said hand pad, said rollers having opposite ends thereof journaled on said side members, adjacent ones of said rollers having ends thereof concentrically journaled on opposite ones of said side members and having opposite ends thereof eccentrically journaled on opposite ones of said side members, and a flexible strap extending across the middle of and above said hand pad and secured at opposite ends thereto.

55 3. A massage device comprising two parallelly

spaced, longitudinally elongated side plates, spacing means extending between and connecting said side plates together, a hand pad comprising a plate extending along and between said side plates and having central lugs on opposite sides thereof pivoted on upper portions of said side plates whereby said hand pad can rock toward either end of said side plates, and a plurality of parallelly spaced rollers positioned endwise between said side plates beneath said hand pad, each of said rollers having projecting from the opposite ends thereof an eccentric pintle and a concentric pintle journaled in journal holes provided in said side plates.

4. A massage device comprising two parallelly spaced, longitudinally elongated side plates, spacing means extending between and connecting said side plates together, a hand pad comprising a plate extending along and between said side plates and having central lugs on opposite sides thereof pivoted on upper portions of said side plates whereby said hand pad can rock toward either end of said side plates, and a plurality of parallelly spaced rollers positioned endwise between said side plates beneath said hand pad, each of said rollers having projecting from the opposite ends thereof an eccentric pintle and a concentric pintle journaled in journal holes provided in said side plates, adjacent ones of said rollers having their eccentric and concentric pintles journaled in journal holes of different ones of said side plates.

5. A massage device comprising two parallelly spaced, longitudinally elongated side plates, spacing means extending between and connecting said side plates together, a hand pad comprising a plate extending along and between said side plates and having central lugs on opposite sides thereof pivoted on upper portions of said side plates whereby said hand pad can rock toward either end of said side plates, and a plurality of parallelly spaced rollers positioned endwise between said side plates beneath said hand pad, each of said rollers having projecting from the opposite ends thereof an eccentric pintle and a concentric pintle journaled in journal holes provided in said side plates, said hand pad plate having stop lugs depending from opposite end portions thereof for engagement with said side plates to limit rocking of said hand pad relative to said side plates in either direction.
